UNITED STATES PATENT OFFICE.

KARL PÚSKÁS, OF KISUJSZALLAS, AUSTRIA-HUNGARY.

SEEDING-MACHINE.

SPECIFICATION forming part of Letters Patent No. 606,475, dated June 28, 1898.

Application filed February 10, 1897. Serial No. 622,883. (No model.) Patented in Hungary June 6, 1896, No. 4,599; in Belgium June 12, 1896, No. 93,878; in England June 12, 1896, No. 13,009; in Italy June 22, 1896, No. 13,618; in Austria June 25, 1896, No. 46/2,808; in France June 29, 1896, No. 245,081, and in Spain July 11, 1896, No. 19,324.

To all whom it may concern:

Be it known that I, KARL PÚSKÁS, a subject of the King of Austria-Hungary, residing at Kisujszallas, Austria-Hungary, have invented a new and useful Improvement in Apparatus for Sowing Maize and the Like, (for which I have obtained patents in Hungary, dated June 6, 1896, No. 4,599; in France, dated June 29, 1896, No. 245,081; in Belgium, dated June 12, 1896, No. 93,878; in Italy, dated June 22, 1896, No. 13,618; in Great Britain, dated June 12, 1896, No. 13,009; in Austria, dated June 25, 1896, No. 46/2,808, and in Spain, dated July 11, 1896, No. 19,324,) of which the following is a specification.

My invention relates to improvements in corn-planters which are attachable to a plow and operate by the movement obtained from the plow and which automatically drop the grains continuously or at intervals, as may be desired by the operator, into the furrow made by the plow. I attain these objects by the mechanism illustrated in the accompanying drawings, in which—

Figure 1 is a longitudinal section of my machine. Fig. 2 is a front elevation of the same. Fig. 3 is a cross-section of the seeder R, and Fig. 4 is an edge view of the feed-wheel. Similar letters refer to similar parts throughout the drawings.

B is an upright carrying seedbox. F, G, and Y are sections of the seedbox. f and g are separating-walls in the seedbox. D is the discharging-tube. C is a tube connecting with D. V is a chamber. N is the ground-wheel. d is a projection from the seedbox, to which tube D is attached.

In the construction of my improved corn planter or seeder I use an upper seedbox fastened to the upright B, divided into three compartments F, G, and Y by movable slides or partitions f and g, fastened to the sides of the compartments. To the third compartment Y, I fasten a rotary pipe D, and on this is arranged a seeding or delivery pipe C, fastened to the plow and movable up and down by means of an iron arm or bracket fastened by means of a stirrup.

The device is attached to the plow-handle by the strap P and by means of the iron arm c from the rotary pipe D to the colter, by which it is fastened vertically to the plow, with the wheel N supporting the device on the ground. The first compartment F of the seedbox is filled with corn, the slide f being previously placed in a position to prevent the corn entering the second compartment G too rapidly. When the plow is set in motion, drawing with it the planting device, the wheel N rotates, and by means of the chain-gearing O rotates the feeding-wheel R, which, by means of a feed-cup, takes the corn falling through from the first compartment F, carries it, one grain at a time, (or grain by grain,) to the opening of the next compartment G, and allows it to be distributed continuously or at intervals into the furrow through the rotary pipe and the delivery-pipe C, which is an extension thereof and movable thereon. The cover and sides of the device may be opened to control the working of the machine. In the operation of the planter the construction permits the distribution of the corn continuously or at intervals, as may be desired.

Having thus described my device, what I claim as new, and desire to secure by Letters Patent, is—

In a corn-planter attachment to plows the combination of a seedbox on an upright supported by a wheel running with the plow and attached thereto, divided into three chambers by movable sliding partitions, and containing a feeding-wheel conveying the corn from the second to the third chamber from which the corn is discharged through a rotary pipe and delivery-tube into the furrow motion being obtained by means of a chain-gearing engaging with the supporting-wheel as and for the purpose above specified.

In testimony that I claim the foregoing as my invention I have signed my name in presence of two subscribing witnesses.

KARL PÚSKÁS.
